UNITED STATES PATENT OFFICE.

HARRY ARTHUR KIMBER, OF NEW ROCHELLE, NEW YORK.

PULVERIZER.

Application filed August 20, 1926. Serial No. 130,371.

This invention relates generally to rotary devices for pulverizing or breaking up coal and similar materials to either powder-like or granular condition such as will enable it 5 to pass through woven screens of different degrees of fineness of mesh, and is designed to increase the efficiency and certainty of action of such apparatus.

More particularly the invention embodies 10 certain improvements in apparatus of the above description in which a plurality of beaters or paddles are revolved in connected circular chambers formed in a cylindrical casing, the material to be pulverized being 15 fed in at one end of said casing near the center thereof and the pulverized product expelled from the circumference of the chamber at the opposite end of said casing. To this end the invention comprises the pro- 20 vision, in apparatus of this type, of certain inclined beater blades or paddles and cer- 25 tain inclined stationary baffles between or adjacent successive sets of paddle wheels, by the interaction of which portions of the 30 material being operated on are transferred from one chamber to another, or temporar- 35 ily confined in one chamber, all in such a way that their pulverization is accomplished with certainty and with the least possible consumption of power.

The best form of apparatus at present known to me embodying my invention is illustrated in the accompanying two sheets of drawings in which

35 Fig. 1 is a vertical axial section of the entire apparatus.

Fig. 2 is a detail plan view of a portion thereof with the upper part of the casing removed.

40 Fig. 3 is a detail side view with parts broken away of one rotary beater and one set of baffles, being essentially a side view of the parts shown in Fig. 2.

Fig. 4 is a diagrammatic development of 45 the preferred arrangement of beaters and baffles, and

Fig. 5 is a section on line 5—5 of Fig. 1.

Throughout the drawings like reference 50 characters indicate like parts. 1 is the cylindrical casing of the pulverizer to one end of which the coal or other material crushed preliminarily to standard size is fed through opening 2^a in graduated quantities by a suitable feeding device 2. In this casing rotate 55 sets of beaters, as 4, 4^a, and 5, 5^a, carried by a revolving shaft 3, driven by coupling 3^a

from any suitable prime mover. Disposed around the cylindrical casing between or adjacent the different sets of beaters are stationary baffles 6, 6, and 7, 7. The finest material is ultimately sucked away from the beaters by fan 10 on shaft 3 and then blown out through the discharge passages 11.

In general character the above described structure and mode of operation are not 60 novel, and my invention consists in certain improvements in details of construction which produce a new mode of operation and improved results, and which I will now describe:

The first set of paddles 4^a mounted on 65 rotary disc 4, and forming the first beater encountered by the entering raw material, have their working faces slightly inclined toward the second set 5^a, mounted on disc 70 5, and the space between the two sets is partly occupied by a plurality of short baffle plates 6, extending inwardly from the casing circumference. These baffle plates 6 have 75 concave or sloping faces (as shown in Fig. 4) against which the material is thrown from beaters 4^a, and are supported by rib- 80 like projections 6^a from the interior of casing 1, or from a ring 6^b mounted therein. The faces of these baffles are not arranged 85 exactly radially of the chamber but with a slight backward inclination to the radii thereof, as shown in Fig. 3.

The result of these features of construction is that when inclined paddles 4^a revolve 90 in the direction of the arrow in Fig. 3, a considerable portion of the material beaten up or knocked down by them is thrown against baffles 6, the concave or sloping faces of 95 which ensure the rebounding of the particles of material into the path of the second set of paddles 5^a by which they are consequently struck with increased force due to the paddles and particles travelling in opposite directions. Other portions of the material 100 which have been broken down to a finer state of pulverization by being knocked back and forth between paddles 4^a and the hard lining rings 1^a of casing 1 are dragged by the fan suction through the central open space 8 105 from the zone of the first beater 4, 4^a, to that of the second one 5, 5^a.

Paddles 5^a, 5^b, have no inclination, and as the second set of short baffles 7, 7, between said paddles 5^a and the fan 10 have faces 7^a 110 curved or sloping toward paddles 5^a, all that portion of the material which is of large

enough mesh to have individual solidity and momentum is thrown against these baffles and by them turned back into the path of paddles 5^a. Thus the material is knocked down again and again until the continued impact and friction of paddles and baffles reduces it to a condition of such fineness and fluffiness that it has little weight and momentum relative to its area of surface exposed to air resistance. The portion so pulverized is not thrown out centrifugally but is sucked out laterally by fan 10 through the central open space 9 and then blown out through discharge passages 11. The faces 7^a of the baffles 7 may also be made straight, as shown in dotted lines in Fig. 4.

Among the advantages of the invention may be mentioned the efficient action of the paddles 5^a, due to the fact that a large portion of the particles struck by them are travelling in the opposite direction, having ricochetted from the inclined paddles 4^a and concave or sloping inclined baffle faces 6; the prolonged beating received by the material from the second set of beaters 5^a because of the "feed back" action of baffles 7, and the robust and durable character of the baffle systems resulting from their short, rib supported structure. This baffle construction at the same time does not clog up the air passage from inlet 2^a to fan 10, because of the ample central openings 8 and 9 left by these relatively short baffles. It has been heretofore proposed to insert radial baffle strips between sets of beaters, but as these extended all the way to the central shaft they had to be made thin in order not to clog up the air passages, and because of this frail structure they soon broke or wore out under the constant pounding and attrition experienced from the masses of flying coal or other material being treated. Also the inclination of the baffle faces 6, toward the center of the casing, as shown in Fig. 3, contributes to efficiency in action as the material striking them is more apt to rebound into the path of the paddles 5^a than to pack out against the annular lining 1^a, as is the case when the baffles extend exactly radially of the chamber, thereby tending to form pockets with the enclosing casing into which pockets masses of material are thrown and thereafter held to serve as cushions against which moving particles are thrown, thus absorbing power without producing useful results in the breaking up and grinding down of the material being treated, which is mainly accomplished by direct contact with the paddles, baffles or casing walls. This inclination of the beater faces in effect serves to make them more nearly perpendicular to the line of travel of particles of ma-

terial thrown against them by the beaters, and consequently the rebound of said particles is more apt to throw them back into the path of the beaters.

By the rebounding of the particles a heavier blow is struck, thereby reducing the materials more quickly and making it possible to get a large capacity from a relatively small machine with the minimum of chambers and power.

Obviously various changes could be made in the angularity or curvature of the working surfaces used as above explained in carrying out my invention, and in the relative proportions of the various parts, without departing from the substantial novelty herein disclosed, or from the underlying principles of my invention, so long as the general arrangement of parts and mode of cooperation above set out, are retained.

Having described my invention, I claim:

1. In a rotary pulverizing apparatus the combination, with a casing containing a generally circular chamber, of a series of sets of rotary beaters revolving in said chamber, and a set of stationary baffles located in said chamber between said sets of beaters and having their faces against which the material is thrown sloped to facilitate the rebounding toward one set of beaters of the material thrown against them by another set.

2. A combination such as defined in claim 1 in which the paddles of one of said sets of beaters are inclined laterally toward said baffles.

3. A combination such as defined in claim 1 in which said baffle faces are concave.

4. A combination such as defined in claim 1 in which said baffle faces are also inclined to the radii of the casing so as to be nearly perpendicular to the path of the particles thrown against them by said beaters.

5. In a rotary pulverizing apparatus comprising a casing, a set of rotary beaters and a fan both revolving in said casing upon a common axis, the combination, with said above recited elements, of short radial baffles set around the periphery of said casing between said beater and fan, which baffles have inclined faces on their sides adjacent the beater, whereby the material thrown against them by said beater is returned to the path of the beater paddles until it becomes fine enough to be sucked out by the fan through the central opening left by the baffles.

6. A combination such as described in claim 5 in which said inclined faces are curved concavely.

HARRY ARTHUR KIMBER.
